Patented Aug. 21, 1956

178,578

GOLFER'S ACCESSORY TOOL OR THE LIKE

Alfred Pelzmann, Glencoe, Ill.

Application February 29, 1956, Serial No. 40,416

Term of patent 7 years

(Cl. D9—2)

Fig. 2.

Fig. 3.

I claim:

The ornamental design for a golfer's accessory tool or the like, as shown.
